(57) **CLAIM**

The ornamental design for a bezel ring with pin, as shown and described.

DESCRIPTION

FIG. 1 is a top view of the invention;

FIG. 2 is a bottom view thereof;

FIG. 3 is a front view thereof;

FIG. 4 is a back view thereof;

FIG. 5 is a left side view thereof;

FIG. 6 is a right side view thereof;

FIG. 7 is a top perspective view thereof;

FIG. 8 is a bottom perspective view thereof; and,

FIG. 9 is an exploded view thereof.

The portions of the watch depicted in broken lines form no part of the claimed design.

1 Claim, 3 Drawing Sheets
